TRUMP INDICATOR OR SIMILAR ARTICLE

Harold D. Marshall, Laguna Beach, Calif.

Application February 12, 1957, Serial No. 44,847

Term of patent 14 years

(Cl. D34—13)

The figure in the drawing is a perspective view of a trump indicator or similar article showing my new design. The opposite side presents the same appearance as the side shown.

I claim:

The ornamental design for a trump indicator or similar article, substantially as shown and described.
